Fig.15

FIG. 1 is a front elevational view of a serving cart for food and the like showing the new design;

FIG. 2 is a rear elevational view thereof;

FIG. 3 is a left side elevational view thereof, the right side being substantially a mirror image of the left side shown herein;

FIG. 4 is a top plan view thereof;

FIG. 5 is a bottom plan view thereof;

FIG. 6 is a front perspective view thereof;

FIG. 7 is a rear perspective view thereof;

FIG. 8 is a sectional view thereof taken on the line 8—8 of FIG. 1;

FIG. 9 is a front elevational view of a serving cart for food and the like showing a second embodiment of my new design;

FIG. 10 is a rear elevational view of the embodiment shown in FIG. 9;

FIG. 11 is a left side elevational view of the embodiment shown in FIG. 9, the right side being substantially a mirror image of the left side shown herein;

FIG. 12 is a top plan view of the embodiment shown in FIG. 9;

FIG. 13 is a bottom plan view of the embodiment shown in FIG. 9;

FIG. 14 is a front perspective view of the embodiment shown in FIG. 9; and

FIG. 15 is a rear perspective view of the embodiment shown in FIG. 9.

This application contains subject matter from my applications Ser. No. 288,345 and Ser. No. 288,346, both

filed Sept. 12, 1972 and now abandoned, and insofar as it contains subject matter not common to said application Ser. No. 288,345 it is a continuation-in-part of that application, and insofar as it contains subject matter not common to said application Ser. No. 288,346 it is a continuation-in-part of that application.

I claim:

The ornamental design for a serving cart for food and the like, as shown and described.
